(57) **CLAIM**

The ornamental design for a wall mountable wire mirror assembly, as shown and described.

DESCRIPTION

FIG. 1 is a perspective view showing the new design for a wall mountable wire mirror assembly;

FIG. 2 is a front view thereof;

FIG. 3 is a rear view thereof;

FIG. 4 is a top view thereof;

FIG. 5 is a bottom view thereof; and,

FIG. 6 is a side view thereof; the opposite side view thereof being a mirror image of the side view shown.
